UNITED STATES PATENT OFFICE

GEORGE F. WIKLE, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS

BUILDING CORE

Application filed November 14, 1925. Serial No. 69,122.

My invention relates to an improvement in collapsible building cores used in the manufacture of pneumatic tire casings and has for its object a construction which will facilitate removal of the casing from the collapsed core.

In general my invention consists in so constructing the tips of certain of the core sections as to decrease the obstruction offered to the removal of the casing by the collapsed sections. It is among the objects of my invention to provide a construction such that the core tips will drop freely under the action of gravity without frictional resistance between the adjacent faces of the tip and core body. In the drawings which illustrate one embodiment of my invention

Figure 1 is a side view of the tip of a core section,

Figure 2 is a front view of the structure 20 shows in Figure 1,

Figure 3 is a section substantially on line 3—3 of Figure 1, and

Figure 4 is a diagrammatic view of two core sections in collapsed relation showing 25 the manner in which my improved core operates.

In the drawings I have shown a core collapsible in four sections designated as 1, 1 and 2, 2. In order to secure proper alignment the faces of the sections are provided with interfitting portions 3 having irregular edges 4. This latter is a conventional feature and forms no part of my invention. In carrying out my invention I form the tip portion of the sections 1, 1 as movable units 5, hinged to the body of the section by a link 7 pivotally engaging rods 8 and 9 secured respectively in the body 1 and the tip 5. The manner of accomplishing the pivoted connection is clearly shown in Figure 3 where the ends of rod 8 are shown anchored at 11 in the walls of the core and the link 7 is secured in adjusted longitudinal position on the rod by collars 12 provided with set screws 13. Link 7 is similarly adjustably mounted on rod 9. The engaging faces of tip 5 and core body 1 are formed by engaging plates 14 and 16 secured respectively to tip and core body 50 by machine screws 17, plate 14 acting as a

stop to accurately position the tip as shown in Figure 1.

As will be obvious, when the core is collapsed as shown in Figure 4 the tips 5 drop by gravity thus decreasing the normal 55 distance from tip to tip of sections 1. It will also be obvious that as the tip drops it swings slightly away from the core body permitting free movement. When the collapsed core is set up sections 1 separate and sections 2, moving outwardly to complete the annulus, engage tips 5 and move them into the position shown in Figure 1.

It will be understood that any conventional type of collapsing chuck may be used 60 to operate the core sections.

Having described an illustrative embodiment of my invention, I claim:

1. In a collapsible core, a composite section subdivided into a main and a small supplementary section forming a tip of the section, the supplementary section being pivoted to the main section upon a pivot located within the body of the composite section.

2. In a collapsible core a composite section subdivided into a main and a small supplementary section forming a tip of the section, the supplementary section being internally pivoted to the main section and comprising less than a complete cross-section of 75 the core.

3. In a collapsible core, a core section having its tip portion, comprising less than a complete cross-section of the core, divided from the main section by an angular cut and 80 a pivotal connection between the body of the section and the tip portion.

4. A collapsible core section having its tip portion, comprising less than a complete cross-section of the core, formed as a separate 85 element movable with respect to the body of the core section to separate the adjacent faces of the tip and body.

5. A collapsible core section having its tip portion, comprising less than a complete cross-section of the core, formed as a separate 95 element, and means connecting the tip to the body of the section permitting relative movement between the body and tip to decrease the effective length of the section.

6. A collapsible core section having its tip portion, comprising less than a complete cross-section of the core, formed as a separate element, and means connecting the tip to the body of the section permitting spaced bodily movement between the body and tip, the engaging faces of the body and tip being provided with means to secure alignment thereof when in operative position.
- 10 7. A collapsible core section having its tip portion, comprising less than a complete cross-section of the core, formed as a separate element, and a link connecting the tip of the body of the section, said link adapted to permit transverse adjustment of the tip and body portions.
- 15 8. A collapsible core section having its tip portion, comprising less than a complete cross-section of the core, formed as a separate element movable with respect to the body of the section and means to secure transverse and vertical alignment of the tip with respect to the body portion.
- 20 9. A collapsible core section having its tip portion, comprising less than a complete cross-section of the core, formed as a separate element, a link connecting the tip and the body of the section, means to permit transverse adjustment of the link with respect to both the tip and the body of the section, and abutments formed respectively on the adjacent faces of the tip and the body of the section to secure vertical alignment thereof.

In testimony whereof I have signed my
35 name to the above specification.

GEORGE F. WIKLE.
